DESIGN FOR A SOCK OR SIMILAR ARTICLE

Anne Yandell, New York, N. Y.

Application July 29, 1944, Serial No. 114,619

Term of patent 14 years

(Cl. D47—7)

To all whom it may concern:

Be it known that I, Anne Yandell, a citizen of the United States, residing in New York, in the county of New York and State of New York, have invented a new, original, and ornamental Design for a Sock or Similar Article, of which the following is a specification, reference being had to the accompanying drawing forming a part thereof, wherein:

Fig. 1 is a top view of a sock showing my new design.

Fig. 2 is a side view, slightly in perspective, and Fig. 3 is a rear elevational view thereof.

I claim:

The ornamental design for a sock or similar article, as shown.

ANNE YANDELL.
